Wheels in Channels.

No 8219X

Patented May 24, 1834.

Rufus Porter of Billerica, Mass. 8299x
Letter Patent (May 24, 1854)

The Schedule referred to in these Letters Patent (making part of the same, containing) a description in the words of the said Rufus Porter himself of his improvement in Boats.

To all to whom these presents shall come. Be it known that I, Rufus Porter, of Billerica in the County of Middlesex, State of Massachusetts have invented a new & useful improvement in boat; and that the following is a full and exact description of the construction of the said Boat, as invented by me.

The boat is made in the shape or form which may be denominated a pointed hull, being pointed in the centre, but tapering gradually to a point at each end, and made like a pointed scull to that of a cask and consisting of long pointed ~~planks~~ ^{boards} or planks which are fastened by bolts, spikes or screws, to circular timbers which are ~~placed~~ ^{placed} in a convenient ~~but~~ ^{at} ~~able~~ ^{able} ~~distance~~ ^{distance} and are of various diameters, being larger near the centre of the boat but smaller toward the ends, so that each plank may conform to a uniform curve from bow to stern. The proportion of the length of the boat to the diameter thereof should be as twenty to one, but may be varied as circumstances may require. The principal mode in which I contemplate using ~~two~~ ^{two} of the above description is to place two such boats parallel to each other and at such a distance from each other as shall be equal to one tenth of the length of the boat ~~so~~ ^{so} that when there is that situation by means of a beam, extending across ~~the~~ ^{the} ~~one~~ ^{one} boat to the other (the end of each beam being firmly secured to each boat) which shall be a deck or floor on which may be erected machinery for propelling the boat cabin for passengers &c. The paddle wheel (in case the boats are propelled by人力 or horse power) being placed between the two boats, which however when connected together with the deck &c are considered as constituting but one boat but nevertheless in some cases, the single boat would be preferable. The principal claim of originality in this invention is the peculiar shape of the single boat applied to it alone, whether solid or hollow.
